United States Patent Office

Des. 215,310
Patented Sept. 23, 1969

215,310

TOOL STORAGE CABINET OR THE LIKE

Robert G. Marks, 35 Cottage St.,
Watertown, Mass. 02172

Filed Feb. 21, 1968, Ser. No. 10,669

Term of patent 14 years

Int. Cl. D6—01

U.S. Cl. D33—19

FIG. 1.

Fig. 2.

FIGURE 1 is a front elevation of a tool storage cabinet or the like showing my new design, and

FIGURE 2 is a front perspective view with one of the sliding peg board compartments in extended position. The side not shown is like the side shown while the top and back are conventionally flat.

I claim:

The ornamental design for a tool storage cabinet or the like, as shown and described.
